UNITED STATES PATENT OFFICE.

JOHN M. HOTHERSALL, OF BROOKLYN, NEW YORK, ASSIGNOR TO AMERICAN CAN COMPANY, OF NEW YORK, N. Y., A CORPORATION OF NEW JERSEY.

CONTAINER.

1,236,437.

Specification of Letters Patent. Patented Aug. 14, 1917.

Application filed June 7, 1915. Serial No. 32,469.

To all whom it may concern:

Be it known that I, JOHN M. HOTHERSALL, a citizen of the United States, residing in Brooklyn, in the county of Kings and State of New York, have invented a new and useful Improvement in Containers, of which the following is a specification.

My invention relates in general to containers and has more particular reference to 10 containers adapted for the packaging of powder or pulverized material, such as talcum powder and the like.

A principal object of the invention is the provision of such a container made without 15 solder and having a side seam interlocked to adjacent an end thereof, the body of said container being so constructed that a bottom crimped thereupon and embracing the side seam beneath the interlocking portion will 20 not permit leakage of the contents.

A further object of the invention is the provision of a non-leaking container for 25 pulverized materials, wherein no bulky connection between the side edges of the body will be inclosed or embraced with the seam in the bottom.

A still further object of the invention is the provision of a cheap, durable and simple 30 container of pleasing appearance.

Other objects and advantages of the invention will be apparent as it is better understood from the following description when considered in connection with the accompanying drawing illustrating a preferred embodiment thereof.

On the drawing,

Figure 1 is a container embodying my invention;

Fig. 2 is a partial view of a blank from 40 which the body of said container is formed;

Fig. 3 shows the blank folded and ready for bending into the form of the body;

Fig. 4 is an end elevation of the blank in 45 the form shown in Fig. 3 and looking from the top end of this blank;

Fig. 5 is a sectional view of the finished container;

Fig. 6 is a perspective enlarged view showing 50 the formation of the seam; and

Fig. 7 is a section taken substantially on the line 7—7 of Fig. 5.

For the purpose of illustrating my invention I have shown it embodied on the drawing in a container comprising an oval body 55 10, a sifter top 11 and a bottom 12. The

parts shown are of the general form and configuration of the oval talcum powder boxes commonly in use. The body 10 is formed of a sheet cut to a suitable blank 13. My invention relates to the formation of the container body and its connection with the bottom wall 12, and therefore only the lower portion of the blank 13 is shown. At one bottom corner this blank is notched at 14 and is notched also at 15 at the other bottom corner in a different form of notch. The notch 14 extends upwardly of the bottom edge a distance equal or substantially equal to the width of the crimped seam 16 by which the bottom is connected with the body in the 60 present instance. The notch 15 extends upwardly a like distance, but this notch is materially wider than the notch 14. The notch 14 has a width equal to the depth of the hook edge 17 at this side of the container, as seen 65 in Fig. 3, this hook edge being formed by bending inwardly the portion of the edge above the notch. The notch 15 is provided with an inwardly extending tongue 18 positioned midway its length, and the adjacent 70 longitudinal edge of the blank is folded back upon itself on the dotted line 19. It is again folded on the dotted line 20 and inwardly on the dotted line 21 to form a pocket or recess 22, as seen in Fig. 4, in 75 which may be engaged the hook edge 17 of the other side to form the body. The dotted lines 20 and 21 extend upwardly from the side edges of the tongue 18 and this tongue is preferably of sufficient length to extend 80 downwardly beneath the edges interlocked through the engagement of the hook 17 in the pocket 22. In the present instance, the tongue 18 extends downwardly to the bottom edge 23 of the blank so that it may be 85 considered that instead of a single notch 15, two notches 15 and 23, one on each side of the tongue, are provided. The tongue 18 is not bent greatly in the formation of the can and only the edges of the blank have been interlocked, which is disposed as is shown in 90 Fig. 6.

After the blank has been formed, as just described, and the edges interlocked, the same is flattened down as indicated in Fig. 105 7 into a tight interlocking connection. The bottom 11 is crimped or otherwise secured in place with the tongue 18 extending into the seam, the body of the bottom being preferably disposed close to the lower end of the 110

interlocking connection between the side edges of the body blank. When thus constructed and arranged it will be manifest that the tongue 18 prevents leakage between the ends of the side edges of the blank located beneath their interlocking connection, and this without requiring the formation of a bulky or unsightly spot in the connection between the body and the bottom. In securing the bottom in place the tongue is held in tight metal to metal contact with the adjacent faces of the edge portions of the blank so that powder cannot seep through between these edges and beneath the interlocking connection.

It is thought that the invention and many of its attendant advantages will be understood from the foregoing description, and it will be apparent that various changes may be made in the form, construction and arrangement of the parts without departing from the spirit and scope of the invention or sacrificing any of its material advantages, the form hereinbefore described being merely a preferred embodiment thereof.

I claim:

1. A container comprising an interlocked side seam terminating short of an end of said container, and an end lip in line with the seam and disposed behind the edges of the material forming the seam beyond its interlocking part and separate from the seam flange along each of its longitudinal sides.

2. A container comprising an interlocked side seam terminating short of an end of said container, and an end lip extending downwardly from said seam and disposed behind the edges of the material forming the seam beyond its interlocking part and separated from the seam flange along each of its longitudinal sides.

3. A container having a side wall formed of a blank notched at the corners of a side, the blank at one end being provided with a tongue 18.

4. A container having a side wall formed of a blank notched at the corners of a side, the blank at one end being provided with a tongue 18, said blank being foldable to dispose said tongue behind the adjacent edges of a seam at the end of the body of said container.

5. A container comprising a body and a closure crimped about an end thereof, said body having interlocking side edges inwardly of said closure and being provided with a tongue extending into the crimped connection of said closure with said body, said tongue covering the side edges within the crimped connection.

Signed in the presence of two subscribing witnesses.

JOHN M. HOTHERSALL.
